UNITED STATES PATENT OFFICE.

CHRISTEN MICHELSEN, OF UNION GROVE, WISCONSIN.

DITCHING-MACHINE.

SPECIFICATION forming part of Letters Patent No. 374,690, dated December 13, 1887.

Application filed June 13, 1887. Serial No. 241,095. (No model.)

To all whom it may concern:

Be it known that I, CHRISTEN MICHELSEN, of Union Grove, in the county of Racine, and in the State of Wisconsin, have invented certain new and useful Improvements in Ditching-Machines; and I do hereby declare that the following is a full, clear, and exact description thereof.

My invention relates to ditching-machines; and it consists in certain peculiarities of construction and combination of parts, to be hereinafter described with reference to the accompanying drawings, and subsequently claimed.

In the drawings, Figure 1 represents a vertical longitudinal sectional view of a ditching-machine constructed according to my invention, the section being taken on line 1 1, Fig. 2; Fig. 2, a plan view of the same; Fig. 3, a front end view; Fig. 4, a rear end view; Fig. 5, a section on line 5 5, Fig. 1; Fig. 6, a section on line 6 6, Fig. 5; Fig. 7, a section on line 7 7, Fig. 6; and Fig. 8, a sectional view of the rear end of the conveyer.

Referring by letter to the drawings, A represents an axle to which is journaled traction-wheels B, and fast on the inside of these wheels are gear-wheels C, that mesh with pinions D on a shaft, E, the latter having its bearings on longitudinal timbers F, clipped or otherwise secured to said axle and united by transverse timbers F' F'', said timbers forming the frame of my machine.

Loosely connected to the axle A, by means of clips a or other suitable means, are the rear ends of arms G, the front ends of said arms being provided with eyes b, through which passes a guide-rod, c, that is fastened to the front timber, F', of the frame. The arms G are provided with guides d for the adjustable standards H' of a ditching-plow H, said standards being united at their upper ends by a bifurcated hand-lever, H'', terminating near the driver's seat I, the latter being upon a spring, I', bolted to the timber F' of the frame. The plow-standards H' are pivotally connected to a yoke, J, and a flexible connection, J', passed over an anti-friction roller, e, journaled in an arm, J'', projecting from the front timber, F', of the frame, serves to unite said yoke with a hand-lever, K, the latter being provided with rack-teeth to engage a suitable stop, f', ar-

ranged on a bracket, f, that unites the upper ends of said plow-standards.

Pivots connected to the yoke J just in front of the plow-standards H', and passed through guides d' on the arms G, are arms L', that carry wheel-colters L, the upper ends of said arms being united by a rod, g, to which is secured a hand-lever, M, provided with rack-teeth to engage a stop, f'', on the bracket f, that forms part of the lever H'', uniting said plow-standards, and I prefer to employ a spring, h, to hold the lever down upon said stop.

Journaled in the plow-standards H' is the shaft N' of a roller, N, said shaft passing through side boards, O, provided with guide-strips O' for an endless carrier, P, and the rear ends of each side board have slots i to receive the bushings j of a roller, Q, loose on a square shaft, R, on which are arranged arms S, said shaft being journaled in the longitudinal beams F of the frame. Flexible connections S' have their rear ends connected to the pivoted arms S and their front ends wound on drums T', arranged upon a shaft, T, that has its bearings on the longitudinal timbers of the frame.

Fast on the shaft T is a socket-head, T'', for a hand spike, U, this construction serving to tighten the endless carrier P by moving the roller Q in an outward direction, and when thus actuated reverse movement is prevented by means of a pawl, T'', pivoted to one of the longitudinal timbers F and arranged to engage a ratchet-wheel, T', on said shaft.

Fast on the squared shaft R are sprocket-wheels R', and over the latter and similar wheels, E', on the pinion-shaft E are passed drive-chains V, this arrangement of parts serving to actuate the endless carrier P.

Suspended from the rear ends of the side boards, O, is a triangular two-way chute, W, that normally delivers the dirt carried back from the plow on each side of the furrow, said chute being provided with a scraper, w, that impinges against the endless carrier. The apex 95 of the two-way chute is provided with eyes k, through which are similar eyes on a board, W', is passed a pin, m, to form a hinge-joint, so that said board may be adjusted to shut off either way of said chute, and thus cause the 100 dirt to fall on only one side of the furrow, as best illustrated in Fig. 4.

I provide the standards H' of the plow H with a series of perforations, n , and by means of a pin, o , passed through any one of the perforations in each standard, support said plow 5 at the desired elevation. The colter-arms L' are also provided with a series of perforations, p , and can be vertically adjusted accordingly as their pivots q are engaged by any one of the perforations in each of said arms. The pivoted 10 arms S are also adjustable in a similar manner.

To brackets X , that project from the front transverse timber, F' , of the frame, is connected a pole, Y , and on the opposite side of the machine a singletree, Z , is secured to said timber.

15 By the arrangement of parts just described I am enabled to hitch three horses directly to the machine; but if found more desirable I may secure a three-horse equalizer to the front frame-timber, or otherwise arrange for the 20 draft-power.

In the operation of my machine the plow is under the direct control of the operator through the medium of the hand-lever H^2 , and can be thus readily guided with relation to the furrow, 25 or brought out of the latter to run along the ground without cutting, the colters being similarly adjusted by the hand-lever M .

The plow, colters, and conveyer may be arranged in the center of the machine, as shown, 30 or laterally adjusted on either side of said center, as may be desirable, the guide-rod c and the eyes b on the arms G being provided with perforations to receive pins b' , that serve to hold said plow, colters, and conveyer in the 35 position to which they may be adjusted.

By operating the hand-lever K the draft of the plow is readily regulated by the operator, so that said plow will make a deep or shallow furrow, as may be desirable, the strain being 40 upon the yoke J , above described.

Having thus fully described my invention, what I claim as new, and desire to secure by Letters Patent, is—

1. In a ditching-machine, the combination 45 of a suitable frame, an axle secured to the frame and carrying traction-wheels, arms loosely connected to the axle and supported by a front timber of said frame, a suitable plow having vertical standards supported on the arms and 50 united by a bifurcated hand-lever, a yoke pivoted to the standards, a hand-lever flexibly connected to the yoke, and a conveyer arranged in the rear of the plow, substantially as set forth.

55 2. In a ditching-machine, the combination of a suitable frame, an axle secured to the frame and carrying traction-wheels, arms connected to the axle and supported by a front timber of the frame, a suitable plow having 60 vertical standards united by a bifurcated hand-lever, a yoke pivoted to the standards, lever-arms pivoted to the yoke and carrying wheel-colters, a hand-lever flexibly connected to said yoke, and a conveyer arranged in the rear of 65 the plow, substantially as set forth.

3. In a ditching-machine, the combination

of a suitable frame, an axle secured to the frame and carrying traction-wheels, arms connected to the axle and supported by a front timber of said frame, a suitable plow having 70 vertically-adjustable standards united by a bifurcated hand-lever, a yoke pivoted to the standards, vertically-adjustable lever-arms pivoted to the yoke and carrying wheel-colters, a hand-lever flexibly connected to said 75 yoke, and a pivotally-adjustable conveyer arranged in the rear of the plow, substantially as set forth.

4. In a ditching-machine, the combination 80 of a suitable frame, an axle connected to the frame and carrying traction-wheels, laterally-adjustable arms connected to the axle and supported by a front timber of said frame, a suitable plow having vertical standards united by a bifurcated hand-lever, a yoke pivoted to 85 the standards, lever-arms pivoted to the yoke and carrying wheel-colters, a hand-lever flexibly connected to said yoke, and a laterally-adjustable conveyer arranged in the rear of the frame, substantially as set forth. 90

5. In a ditching-machine, the combination 95 of a suitable plow, an endless carrier arranged in the rear of the plow, a two-way chute suspended beneath the rear end of the carrier, and a scraper arranged on the chute to impinge against said carrier, substantially as set forth.

6. In a ditching-machine, the combination 100 of a suitable frame and plow, a conveyer arranged in the rear of the plow and comprising side boards slotted at their rear ends, and an endless carrier passed over rollers that have 105 their bearings in said boards, lever-arms arranged on the shaft of the rear roller and fulcrumed to the frame, a shaft having its bearings on said frame and provided with drums and a socket-head, flexible connections having 110 their ends respectively secured to said lever-arms and drums, and a handspike for actuating said socket-head, substantially as set forth.

7. In a ditching-machine, the combination 110 of a suitable frame and plow, the arms G , provided with eyes b , the guide-rod c , plow H , yoke J , lever K , flexible connection J' , endless carrier P , roller Q , and square shaft R , substantially as set forth. 115

8. In a ditching-machine, the combination 120 of a suitable frame and plow, the arms G , provided with guides d d' , lever-arms L' , carrying wheel-colters, levers H^2 M , bracket f , provided with the stops f' f'' , yoke J , lever K , flexible connection J' , and a conveyer arranged in the rear of the plow, substantially as set forth.

In testimony that I claim the foregoing I have hereunto set my hand, at Union Grove, 125 in the county of Racine and State of Wisconsin, in the presence of two witnesses.

CHRISTEN MICHELSSEN.
